BRICK VENEER AND ART OF APPLYING
THE SAME

Sam Z. Trachtenberg, Munhall, Pa.

Application January 18, 1934, Serial No. 707,195

15 Claims. (Cl. 72—19)

This invention relates to improvements in the art of brick veneer wall structures and the like, and more particularly to means for and the method of applying and attaching said veneer to 5 form a simulated brick wall.

Among the objects of my invention are to provide a method of assembling and applying a veneer wall of individual slabs or units without the necessity of previously erecting any spacing and 10 securing means therefor over the surface being veneered; to provide each individual veneer slab with a clip or bracket to form a novel veneer unit, whereby said units are capable of selective individual application to a wall or building in any 15 desired pattern or design; to provide a mechanical attaching clip or bracket frictionally engaging the slabs; to provide said clip or bracket with means for gaging the mortar lines between slabs; to provide a veneer unit which may be produced 20 and applied at a minimum cost; and to provide a veneer unit capable of use by the unskilled workman with ease and accuracy.

The invention may be more readily understood by a reference to the accompanying drawing, 25 wherein:

Fig. 1 is a perspective view illustrating the method of assembling a brick veneer wall structure or the like in the manner of my invention;

Fig. 2, a view in elevation of the assembled 30 brick veneer wall;

Fig. 3, an enlarged vertical section taken along the line III—III of Fig. 2;

Fig. 4, an enlarged horizontal section taken along the line IV—IV of Fig. 2;

Fig. 5, an enlarged perspective view of a preferred form of clip or bracket embodying my invention;

Fig. 6, a rear perspective view of a veneer unit showing the application of mortar thereto; and

Figs. 7 and 8, views similar to Fig. 5 of modified forms of clips.

Referring to the drawing, 2 designates a wall or building surface to be covered by brick veneer of the usual and well known form. Generally, 45 said veneer consists of individual thin rectangular ceramic or clay slabs 3 having longitudinal and transverse dimensions corresponding to the respective dimensions of the exposed surface of the usual building brick.

For the purpose of frictionally engaging and attaching the slabs 3 to the wall 2, I provide individual clips or brackets A, preferably formed of sheet metal, and provided with resilient means 50 for application to and frictionally engaging the slabs. In the preferred practice of my invention,

I provide one such clip or bracket A initially applied in embracing relation to one end of each slab 3, providing a novel veneer unit applicable in the manner hereinafter set forth.

In the form of Fig. 4, the clip or bracket A is 5 substantially channel-shaped and consists of a flat rectangular base or body portion 5 have resilient gripping flanges struck up along opposite edges of said body portion. The flanges are preferably converged inwardly a slight amount to 10 effect a resultant tension on the veneer slabs 3 upon engagement therebetween.

Said gripping flanges are arranged in pairs 6—6 and 7—7, separated by intermediate cut-out portions 8 which may extend inwardly of the 15 body portion 5, as shown. The cut-out portions or notches 8 perform the double function of providing individual flexibility for each pair of flanges, and by reason of their width a, form an alinement and mortar gage or indicator for the 20 vertical mortar lines, as hereinafter more fully described. 9 designates a centrally located aperture in the body of the clip for attaching the clip to the wall by means of a nail, screw or the like.

In the practice of my invention, the veneering 25 is commenced at some convenient location on the wall or building, as, for example, at the corner 10 in Fig. 1 and at the bottom of the wall 2 along a base or trim b. A corner or angle veneer slab 3a may be employed by applying a clip A to each 30 end of the slab by means of one pair of flanges of each clip, said flanges resiliently engaging the longitudinal edges of the slab and being flexed outwardly by the insertion of the slab therebetween.

The end edges of the slab are registered in alinement with one extremity of the cut-away portions 8 of the clips. Nails or screws are driven into the wall 2 through the clip holes 9 provided 40 for such purpose, when the slab 3a is correctly positioned with regard to the corner 10 and the horizontal veneer course or row of which it is to form a part.

This initial veneer course or row is continued 45 by successively mounting veneer units formed by applying a clip A, by one pair of its flanges, to an end of a slab 3 as in Figs. 1 and 6, and inserting the free end of the slab of each unit in the exposed pair of flanges of the clip A of the 50 unit applied to the wall immediately prior thereto. The free end of said slab is registered with the remaining extremity of the clip cut-out portion 8 of the previously applied unit, whereby the ends of the slabs 3 and 3a are spaced at a 55

distance a to provide the desired width of the vertical mortar course therebetween.

Additional units are applied in a like manner throughout the course or row until completed, 5 each slab being fitted at one end with a clip A and having its free end inserted in the exposed portion of the preceding clip. Additional rows or courses are applied in parallelism to the initial row by the simple expedient of spacing the 10 same to provide the desired width of the horizontal mortar lines. For example, the standard brick veneer slab is of a thickness corresponding to the usual mortar line, and may be employed by the workman, said slab being inserted edge- 15 wise between the attached row of slabs and the slabs being applied. When so spaced, the clips of the unit or units being positioned may be nailed in place. Obviously, other means may be easily employed for spacing and alining each 20 successive row from the preceding row.

It is to be noted that a veneer wall applied by this method may be readily alined and varied by the workman, much in the same manner as the usual brick wall is assembled. The slabs 25 may be disposed in staggered pattern or selectively arranged, as desired, without the necessity of altering the clip or the method of application.

When the slabs have been positioned, mortar or cement may be applied in the spaces there- 30 between and pointed off to form uniform mortar lines 11. The mortar has an affinity for the ceramic slabs and will assist in retaining the same, and will also have anchorage with the clips A.

In addition to the foregoing practice, I prefer 35 to employ a reinforcing reticulate or open-work sheet 12 superimposed on the surface of the wall 2, entirely covering the same, and secured there- to by means of staples, nails, or the like. An 40 insulating sheet or layer 2a may be interposed between the wall and reticulate sheet 12 if desired.

Upon covering the wall 2 with the insulation 45 2a and the reticulate sheet 12, the veneer units are applied directly over the sheet 12 and as- sembled in the manner described. The rear sur- 50 face of the slab 3 of each unit is preferably sup- plied with a small quantity or patch of mortar, as shown at 13 in Fig. 6. As each unit is ap- plied to the sheet 12, the mortar 13 will be pressed 55 or forced into interlocking engagement with the spaced strands of the reticulate sheet, thereby assisting the retention of the units.

Attention is called to the fact that by the use 55 of the reticulate sheet 12, I have provided an air space 14 between the veneer units and the wall 2 or insulating layer 2a. The mortar at 11 and 13 does not completely fill the space 14 in a continuous layer, and hence air is free to circulate in said space to dry the mortar and prevent moisture from penetrating the wall 2.

From the foregoing, it will be seen that I have 65 provided a veneer wall construction wherein the units are individually secured to the surface being covered, and whereby a proportionate part of the load is assumed by each unit. Hence, the tendency of the completed wall to crack is materially reduced, since the lower units are not over-loaded.

Fig. 7 illustrates a modified form of clip A', 70 having pairs of flanges 6a-6a and 7a-7a, se- 75 parated by intermediate notches 8a. The body portion 5a is formed with an opening 8b having a width a for gaging the width of the mortar space between slabs, as before. 9a designates nail or screw-receiving openings.

I have shown a still further modification in Fig. 8, wherein the clip A'' has a single pair of resilient continuous flanges 6b and openings 8b in the body portion 5b. Veneer slabs 3 will be applied between opposite end portions of the 5 flanges, as will be readily understood.

Various changes and modifications are contemplated within the scope of the following claims.

I claim:

1. In an assembled veneer wall structure, a row 10 of veneer slabs spaced apart in end-to-end relation, individual attaching clips positioned between adjacent slab ends, said clips having flanges for receiving and retaining said slab ends, 15 said flanges being spaced apart longitudinally of the row to provide a gage for determining the space between the slab ends, and means for securing the clips in position.

2. In an assembled veneer wall structure, a 20 row of veneer slabs spaced apart in end-to-end relation, individual attaching clips positioned between adjacent slab ends, said clips having resilient flanges for receiving and frictionally en- 25 gaging said slab ends, means on the clips for gaging the spaces between adjacent slab ends, and means for securing the clips in position.

3. In an assembled veneer wall structure, a 30 row of veneer slabs spaced apart in end-to-end relation, individual attaching clips positioned be- 35 tween adjacent slab ends, said clips having flanges for receiving and retaining said slab ends, each clip having one flange partly severed from the next flange thereof in longitudinal direction so that a gage is provided for determining the position of the slab ends, and means for securing the clips in position.

4. In an assembled veneer wall structure, a 40 row of veneer slabs spaced apart in end-to-end relation, an individual attaching clip positioned at each space between adjoining ends of said slabs, said clip having two pairs of resilient flanges separated by an intermediate cut-out portion, each of said pairs of flanges embracing and 45 frictionally gripping the longitudinal edges of an adjoining slab end, said cut-away portion providing a gage for fixing the space between the slab ends.

5. In a veneer wall structure for application to 50 a wall having a surface to be veneered, a pre- assembled veneer unit comprising a veneer slab having an attaching clip secured to an end there- 55 of to be applied as a unit to said surface, said clip extending beyond the slab end and having resilient flanges for frictionally gripping the free slab end of a similar pre-assembled unit to form an assembled veneer row.

6. In a veneer wall structure, a unit comprising 60 a veneer slab having an attaching clip secured to an end thereof, said clip extending beyond the slab end and having resilient flanges for frictionally gripping the free slab end of a similar unit to form an assembled veneer row, and means on each unit for gaging the spacing between units. 65

7. In a veneer wall structure, a unit comprising a veneer slab having an attaching clip secured to an end thereof, said clip extending beyond the slab end and having resilient flanges for frictionally gripping the free slab end of a similar unit to form an assembled veneer row, and means on each clip for gaging the spacing between units. 70

8. An attaching clip for a pair of veneer slabs including a body portion having a pair of resilient flanges extending therefrom, and means for gag- 75

ing the spacing between said slabs when applied to the clip, as and for the purpose described.

9. An attaching clip for a pair of veneer slabs including a body portion having a pair of resilient flanges for frictionally engaging an end of each of said slabs, and means for gaging the spacing between said slab ends when applied to the clip, as and for the purpose described.

10. An attaching clip for a pair of veneer slabs including a body portion having a pair of resilient flanges for frictionally engaging an end of each of said slabs, said pairs of flanges being separated by a cut-away portion for gaging the spacing between said slab ends when applied to the clip, as and for the purpose described.

11. The herein described method of assembling and applying a veneer wall with a series of individual veneer slabs, consisting in producing veneer units by frictionally engaging one end of each individual slab with an attaching member and with said attaching member partly projecting beyond one end of the slab sufficiently to hold the adjacent slab in line therewith as a preliminary step in the fastening thereof, fixedly positioning one of said units, and successively applying the units in alinement with the fixed unit and with each other, with the free end of each unit entered in the partly projecting portion of attaching member of the preceding unit, and fixing said units in position.

12. In a veneer structure for application to a wall having a surface to be veneered, an attaching

clip, a veneer slab secured to said surface by said attaching clip, said attaching clip having resilient flanges extending beyond an end of the slab, and a pre-assembled veneer unit comprising a second veneer slab having an attaching clip at an end thereof; to be applied to said surface by entering between the said flanges, as and for the purpose described.

13. A pre-assembled veneer unit comprising a veneer slab having an attaching clip secured to and extending beyond one end only of the slab, for individual application and attachment as a unit to a surface to be veneered.

14. A pre-assembled veneer unit comprising a veneer slab having an attaching clip extending beyond one end of said slab, said clip being provided with a pair of resilient flanges, for individual application and attachment as a unit to a surface to be veneered one of said flanges being cut away to provide gage means predetermining the position for a veneer slab to be disposed between said flanges.

15. A pre-assembled veneer unit comprising a veneer slab having an attaching clip extending beyond one end of said slab, said clip being provided with a pair of flanges, for individual application and attachment as a unit to a surface to be veneered one of said flanges having gage means predetermining the position for a veneer slab to be disposed between said flanges.
